ELECTROSTATIC COPIER

Koji Hikawa, Tokyo, Japan, assignor to
Kabushiki Kaisha Ricoh, Tokyo, Japan

Filed Mar. 28, 1972, Ser. No. 238,995

Claim priority, application Japan Sept. 29, 1971

Term of patent 7 years

Int. Cl. D16—03

U.S. Cl. D61—1 Q

FIG. 1

FIG. 2

FIG. 3

FIG. 4

FIG. 5

FIG. 6

FIG. 7

FIG. 1 is a front, top and right side perspective view of an electrostatic copier showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and

FIG. 7 is a bottom plan view thereof.

I claim:

The ornamental design of an electrostatic copier, substantially as shown and described.
